UNITED STATES PATENT OFFICE

GEORGE E. O'HEARN, OF GARDNER, MASSACHUSETTS, ASSIGNOR TO O'HEARN MANUFACTURING COMPANY, OF GARDNER, MASSACHUSETTS, A CORPORATION OF MASSACHUSETTS

DESIGN FOR A WOVEN FABRIC

Application filed January 12, 1931. Serial No. 38,281. Term of patent 7 years.

To all whom it may concern:

Be it known that I, GEORGE E. O'HEARN, a citizen of the United States, residing at Gardner, in the county of Worcester and State of Massachusetts, have invented a new, original, and ornamental Design for Woven Fabric, of which the following is a specification, reference being had to the accompanying drawing, forming part thereof.

The figure is a front view showing my new design.

I claim:

The ornamental design for woven fabric as shown.

GEORGE E. O'HEARN.
